UNITED STATES PATENT OFFICE

ALFRED H. SWAN, OF LOS ANGELES, CALIFORNIA

FOUNTAIN PEN

Application filed June 22, 1929. Serial No. 373,000.

My invention relates broadly to fountain pens and more particularly to a fillable fountain pen of simplified construction having a minimum number of wearing parts.

One of the objects of my invention is to provide a construction of fountain pen which does not require the use of an extraneous instrument for the refilling of the pen or the use of a compressible reservoir in which the fluid within the pen is maintained.

Another object of my invention is to provide a construction of fountain pen wherein a collapsible reservoir is not required for refilling processes and in which the ink or other fluid is maintained out of contact with sliding parts in the pen construction, thereby eliminating undesirable friction of the parts due to the adherence of dried fluid over the surface of the parts.

Still another object of my invention is to provide a fountain pen construction having a large fluid holding capacity which will not require refilling at frequent intervals and in which assurance is given against the leakage of ink from the fountain pen while the pen is not in use.

Other and further objects of my invention reside in the construction of fountain pen as set forth in the specification hereinafter following by reference to the accompanying drawings, in which:

Figure 1 is a central vertical longitudinal section through the fountain pen of my invention; Fig. 2 is a central vertical longitudinal sectional view showing the pen in position for filling the barrel showing the method of exhausting the air from the barrel through the filling process; Fig. 3 is a fragmentary longitudinal cross-sectional view through the pen of Fig. 1 showing the flow of ink cut off and the pen in carrying position; Figs. 4, 5, 6, 7 and 8 are horizontal sectional views taken on the lines 4-4, 5-5, 6-6, 7-7 and 8-8 of Fig. 1; and Fig. 9 is a horizontal sectional view taken on line 9-9 of Fig. 3.

Referring more particularly to the drawings, reference character 1 indicates the outer barrel or shell of the main body of the pen; reference character 2 shows the inner barrel and surrounds the ink or fluid reservoir 5.

Both 1 and 2 are continuous at their lower ends with the solid portion 4. Barrel 2 is continued upwardly into a circular neck 6 which is hollow, the channel 7 being narrower than but continuous with the ink reservoir 5. The channel 7 is open at its upper end. The neck 6 is threaded on its convex circumference and receives a concave thread in the main head-piece 8 when in the closed position. Barrel 3 is attached above to the main head-piece 8 and slides freely between barrels 1 and 2 and extends the full length of the space 3b. The upward progress of barrel 3 is checked by the abutment of the projection 3a against projection 1a. Projection 3a is pierced by segmental spaces as shown at 3c to allow the inflow of air to relieve the vacuum formed in the space 3b as barrel 3 travels upward. Projection 1a is similarly pierced by spaces 1c for a similar purpose. Projection 1a is formed by a multiplicity of segmental members secured by suitable means to barrel 1 such as rivet members 1b. Projection 3a is formed by segmental integral extensions on barrel 3.

The concave thread in the head-piece 8 is pierced at one side to form a port 9 which serves as an air-vent which will be herein-after explained. Portion 8a seals the space 7 when the pen is closed, thus preventing communication between the ink reservoir 5 and the air port 9.

Above the portion 8a is an air valve consisting of a knurled circular grip 10 and a circular neck 11 which slides in a collar 8b. When the air valve is raised it is checked at the proper height by the projection 11b impinging on the collar 8b. Collar 8b is secured in position by any suitable means such as rivets 8d. The neck 11 is hollow, open at the bottom and closed at the top. One side is pierced to form a space 12 which with the air valve raised allows the escape of air entering the neck from the port 9.

At the lower end of the main body the solid portion 4 is so made that it narrows the ink reservoir 5 so that its lower outlet 5a occupies only a portion of one half of its area above. This is accomplished by the overhang of the shelving portion of 4 which ter-

minates in a downward projection 4b which extends at right angles to the section in Fig. 1 across the diameter of the reservoir except for the space 13 as shown in Figs. 8 and 9.

5 The ink reservoir is further narrowed by the projection 4c which will be later explained.

The lowermost section of Fig. 1 is a portion 14 carrying pen point 18 shown in its position when the pen is filled and ready for writing. It is separate from the main body 4 but attached to it by slots or grooves 14a into which projection 4a on barrel 1 extends. The pen portion 14 is hollow, its channel 15 communicating in this position with the ink reservoir 5 through the narrow channel 5a described above. The channel 15 leads to the feed which is attached to its lower end to the pen point 18. Portion 14 can be rotated 180° on portion 4 thereby bringing channel 15 out of communication with ink reservoir 5, the flat surface 14c coming to rest beneath 5a, as shown in Fig. 3, thus preventing ink flowing downward from ink reservoir 5. The rotating action is stopped at the proper points by the projection 14b which in cross-section is a quarter circle. In the writing position, one end of projection 14b abuts against 4b as shown in Fig. 8, while in the closed position the opposite end of projection 14b abuts against 4c shown in Fig. 9. The space shown around 14b has been cut away to reduce friction and to prevent sticking together of rotating parts. The only parts that are bathed in ink which have to slide one on the other are the under surface of 4b against the upper surface of a small bit of 14c—a very minute area in the finished product. Throughout the pen structure, all sliding parts are made to fit snugly with substantially no play or excess movement between the parts.

The operation of the pen of my invention in the filling process is as follows: At the beginning the various parts are arranged as shown in Fig. 1 in writing position. With the fingers of the left hand holding the pen about the outside of barrel 1, the pen nib and feed are placed well below the surface of the ink in a suitable container. The fingers of the right hand grasp the head-piece 8 and rotate it to the left until its concave thread 8c is felt to have disengaged the threaded neck-piece 6. Then by pulling upward on the head-piece 8 the barrel 3 slides upward between barrels 1 and 2, tending to form a vacuum within the ink reservoir 5 thus drawing ink up through the feed. This upward pull is checked when projection 3a abuts against projection 1a, indicating that barrel 3 has been pulled up to its full length. The ink reservoir is now filled with ink, while the interior of barrel 3 is filled with the air that was in the ink reservoir. One of the fingers of the left hand can now be pressed against the outside of barrel 3 to hold it in

position while the right hand releases the head-piece 8 and grasps the lowermost portion 14 at the same time lifting the tip of the pen 18 out of the ink well. The fingers of the right hand now rotate lowermost portion 14 through a turn of 180° to the right. This carries the surface 14c to rest beneath the channel 5a effectively shutting off the downward flow of ink from the ink reservoir for the time being. This action is checked by the projection 14b which traverses a half circle and is stopped by the abutment 4c as shown in Fig. 9. It will be noted that the projection 4b and the point 14d are so placed in relation to the center of rotation that the point 14d is directly under and in contact with 4b in both the open and closed positions.

The fingers of the right hand now release their hold on 14 and grasp the knurled head of the air valve at the very top of the pen at grip 10 and pull the latter upward until stopped by the striking of 11b against the collar 8b. Here the fit is tight enough to permit grip 10 to be maintained in raised position by frictional forces. The right hand now again grasps head-piece 8 and pushes downward to replace barrel 3 to its original position. This is now a safe procedure because the ink cannot flow out of the lower end of the ink reservoir, or, in fact, out of the channel 15 since the lowermost portion 14 is in the closed position. As the barrel 3 descends the air contained in it goes out the top. Reference to Fig. 2 will show that the air will follow a path as indicated by the arrows, namely, out of the top of barrel 3 through the cavity within the concave thread 8c, thence into air port 9 and 9a, thence into channel 11a within the air valve, thence out through the air-vent 12 cut in the neck 11.

When head-piece 8 reaches the threaded neck-piece 6 it is rotated to the right and screwed into its original position. Then the air valve 10 is pushed back into its original place. The lowermost portion 14 is now turned back 180° to the left and the pen is ready to use.

It will be noted that the arrangement of the air passages is such that when the pen is closed the ink cannot enter the air passages or contaminate the moving parts of the air valve. This is accomplished by the sealing of the channel of the neck-piece 6 by the portion 8a and by the cutting of the air port 9 in the side of the thread 8c in such a way that when screwed to neck-piece 6 several turns of the concave thread assist in sealing the air port 9 off from the channel 7.

In the fountain pen of my construction, I avoid the use of a collapsible bag reservoir normally used, which reservoir is subjected to wear and deterioration within a relatively short period of time. The parts of the fountain pen of my invention may be manufactured inexpensively on a quantity production

basis and assembled in such manner that substantially no play exists between the parts insuring an accurately made product with a life depending substantially upon the wearing qualities of the pen point.

5 While I have described my invention in one of its preferred embodiments, I desire that it be understood that modifications may be made and that no limitations upon my invention are intended other than are imposed by the scope of the appended claims.

10 What I claim as new and desire to secure by Letters Patent of the United States is as follows:

15 1. In a fountain pen, an inner barrel having a reservoir for fluid therein, an outer barrel spacially positioned coaxially with said inner barrel and having one end formed integral with the corresponding end of said inner barrel, an intermediate barrel mounted to slide between said inner and outer barrels, a writing head carried by the common portion of said inner and outer barrels, said common portion of said barrels and said writing head being each provided with eccentric flow spaces, said writing head being mounted for rotation relative to said common portion of said barrels for selectively causing or preventing the register of said respective flow spaces, the end of said inner barrel remote from said writing head being exteriorly screw threaded, and an adjustable head rotatable from the exterior of said fountain pen and carried by the end of said intermediate barrel remote from said writing head and screw threaded internally for receiving said screw threaded portion of said inner barrel, said adjustable head being adapted to close said screw threaded end of said inner barrel when said screw threaded portions are engaged, said intermediate barrel being slidable between said inner and outer barrels without access of any writing fluid from said reservoir in said inner barrel to the sliding space between said inner and outer barrels when the screw threaded portion of said adjustable head is disengaged from said inner barrel, and a cap member mounted on said adjustable head and having an interior channel vented to the outer atmosphere and being adjustable with reference to said adjustable head for selectively opening or closing the vent in said cap member to avoid or abut said adjustable head, said adjustable head being internally apertured to permit communication between said reservoir and the channel in said cap member when said adjustable head and said cap member are raised, whereby said inner barrel may be filled with fluid and the air from said inner barrel expelled without the pen structure.

20 2. In a fountain pen, an inner barrel having a reservoir for fluid therein, an outer barrel spacially positioned coaxially with said inner barrel and having one end formed integral with the corresponding end of said inner barrel, an intermediate barrel mounted to slide between said inner and outer barrels, a writing head carried by the common portion of said inner and outer barrels, said common portion of said barrels and said writing head being each provided with eccentric flow spaces, said writing head being mounted for rotation relative to said common portion of said barrels for selectively causing or preventing the register of said respective flow spaces, the end of said inner barrel remote from said writing head being exteriorly screw threaded, and an adjustable head rotatable from the exterior of said fountain pen and carried by the end of said intermediate barrel remote from said writing head and screw threaded internally for receiving said screw threaded portion of said inner barrel, said adjustable head being adapted to close said screw threaded end of said inner barrel when said screw threaded portions are engaged, said intermediate barrel being slidable between said inner and outer barrels without access of any writing fluid from said reservoir in said inner barrel to the sliding space between said inner and outer barrels when the screw threaded portion of said adjustable head is disengaged from said inner barrel, whereby said inner barrel may be filled with fluid and the air from said inner barrel expelled without the pen structure.

25 3. In a fountain pen, an inner barrel having a reservoir for fluid therein, an outer barrel spacially positioned coaxially with said inner barrel and having one end formed integral with the corresponding end of said inner barrel, an intermediate barrel mounted to slide between said inner and outer barrels, a writing head carried by the common portion of said inner and outer barrels, said common portion of said barrels and said writing head being each provided with eccentric flow spaces, said writing head being mounted for rotation relative to said common portion of said barrels for selectively causing or preventing the register of said respective flow spaces, the end of said inner barrel remote from said writing head being exteriorly screw threaded, and an adjustable head rotatable from the exterior of said fountain pen and carried by the end of said intermediate barrel remote from said writing head and screw threaded internally for receiving said screw threaded portion of said inner barrel, said adjustable head being adapted to close said screw threaded end of said inner barrel when said screw threaded portions are engaged, said intermediate barrel being slidable between said inner and outer barrels without access of any writing fluid from said reservoir in said inner barrel to the sliding space between said inner and outer barrels.

30 causing or preventing the register of said respective flow spaces, the end of said inner barrel remote from said writing head being exteriorly screw threaded, an adjustable head rotatable from the exterior of said fountain pen and carried by the end of said intermediate barrel remote from said writing head and screw threaded internally for receiving said screw threaded portion of said inner barrel, said adjustable head being adapted to close said screw threaded end of said inner barrel when said screw threaded portions are engaged, said intermediate barrel being slidable between said inner and outer barrels without access of any writing fluid from said reservoir in said inner barrel to the sliding space between said inner and outer barrels when the screw threaded portion of said adjustable head is disengaged from said inner barrel, and a cap member mounted on said adjustable head and having an interior channel vented to the outer atmosphere and being adjustable with reference to said adjustable head for selectively opening or closing the vent in said cap member to avoid or abut said adjustable head, said adjustable head being internally apertured to permit communication between said reservoir and the channel in said cap member when said adjustable head and said cap member are raised, whereby said inner barrel may be filled with fluid and the air from said inner barrel expelled without the pen structure.

35 4. In a fountain pen, an inner barrel having a reservoir for fluid therein, an outer barrel spacially positioned coaxially with said inner barrel and having one end formed integral with the corresponding end of said inner barrel, an intermediate barrel mounted to slide between said inner and outer barrels, a writing head carried by the common portion of said inner and outer barrels, said common portion of said barrels and said writing head being each provided with eccentric flow spaces, said writing head being mounted for rotation relative to said common portion of said barrels for selectively causing or preventing the register of said respective flow spaces, the end of said inner barrel remote from said writing head being exteriorly screw threaded, and an adjustable head rotatable from the exterior of said fountain pen and carried by the end of said intermediate barrel remote from said writing head and screw threaded internally for receiving said screw threaded portion of said inner barrel, said adjustable head being adapted to close said screw threaded end of said inner barrel when said screw threaded portions are engaged, said intermediate barrel being slidable between said inner and outer barrels without access of any writing fluid from said reservoir in said inner barrel to the sliding space between said inner and outer barrels.

- when the screw threaded portion of said adjustable head is disengaged from said inner barrel, said outer barrel and said intermediate barrel being respectively provided with stops adapted to engage each other and limit
- 5 the sliding movement of said intermediate barrel between said other two barrels, whereby said inner barrel may be filled with fluid and the air from said inner barrel expelled without the pen structure.
- 10 4. In a fountain pen, an inner barrel having a reservoir for fluid therein, an outer barrel spatially positioned coaxially with said inner barrel and having one end formed integral with the corresponding end of said inner barrel, an intermediate barrel mounted to slide between said inner and outer barrels, a writing head carried by the common portion of said inner and outer barrels, said common portion of said barrels and said
- 15 writing head being each provided with eccentric flow spaces, said writing head being mounted for rotation relative to said common portion of said barrels for selectively causing or preventing the register of said respective flow spaces, the end of said inner barrel remote from said writing head being exteriorly screw threaded, an adjustable head rotatable from the exterior of said fountain pen and carried by the end of said intermediate barrel remote from said writing head and screw threaded internally for receiving said screw threaded portion of said inner barrel, said intermediate barrel being slidable between said inner and outer barrels without
- 20 access of any writing fluid from said reservoir in said inner barrel to the sliding space between said inner and outer barrels when the screw threaded portion of said adjustable head is disengaged from said inner barrel,
- 25 and a cap member mounted on said adjustable head and having an interior channel vented to the outer atmosphere and being adjustable with reference to said adjustable head for selectively opening or closing the vent in said
- 30 cap member to avoid or abut said adjustable head, said adjustable head being provided with a lateral aperture in the screw threaded portion thereof and a lateral channel communicating with the interior channel in said
- 35 cap member when said cap member is adjusted in the open position, for sealing said reservoir from access to said last mentioned channels when said screw threaded portion of said inner barrel engages said adjustable head, and placing said reservoir in communication with said channels when said inner barrel is disengaged from said adjustable head, whereby said inner barrel may be filled with fluid and the air from said inner barrel
- 40 expelled without the pen structure.

In testimony whereof I affix my signature.
ALFRED H. SWAN.
